UNITED STATES PATENT OFFICE

MARK H. MARTIN, OF READING, PENNSYLVANIA, ASSIGNOR TO BIRDSBORO STEEL FOUNDRY & MACHINE COMPANY, OF BIRDSBORO, PENNSYLVANIA, A CORPORATION OF PENNSYLVANIA

TRUCK BOLSTER

Application filed April 2, 1930. Serial No. 440,938.

My invention relates to truck bolsters and is concerned more particularly with features relating to strengthening the bolster and effecting an improved distribution of the load imposed thereon.

One object of my invention is to incorporate in a truck bolster provision, involving the use of a truss structure, for more effectively distributing the imposed load throughout the length of the bolster and relieving the high stresses now present in the center portions of standard forms of bolsters.

A further object is to provide a bolster of the character described in which the tension member of the truss constitutes a part of the lower web of the bolster and in which a portion of the center plate load is transmitted to said truss through vertical webs and a reinforcing structure disposed most advantageously for the carriage of the load.

A further object is to provide a truck bolster in which the metal is disposed to increase the vertical and transverse strength thereof, particularly with a view of counteracting the tensile stresses in the bottom web of the bolster, and also to avoid the creation of shrinkage cracks in the casting at the junction of the side walls with the bottom of the bolster.

The present standard A. R. A. truck bolster is of hollow section and various methods have been proposed to adequately support the load imposed on the center plate which is located on the upper web of the section. One of the schemes which has been widely adapted is to interpose a cylindrical column beneath the center plate and the lower web of the bolster, but this construction is characterized by an important operating disadvantage in that it gives rise to a region of localized, critical stresses in the lower web which materially affects the strength of the bolster and requires the section to be considerably heavier than is absolutely necessary.

With this condition in mind, it is the express object of the present invention to devise an arrangement which may be incorporated in the standard form of truck bolster and in which any tendency to localize the stresses

in the lower portion of the bolster is avoided through providing a novel truss structure which serves both to strengthen the bolster and also to better distribute the load throughout the length thereof. This truss structure is connected to the upper web of the bolster by an arrangement of webs which functions to transmit the load to the truss structure and also to materially strengthen the upper web of the bolster in the region of the center plate. This truss and reenforcing structure is supplemented by a disposition of the metal in the side walls of the bolster below a predetermined line interposed between the upper and lower webs thereof, the side walls specifically increasing in thickness below said line down to their junctions with the lower web for the purpose of further strengthening the bolster and making a better casting job at the junctions noted, avoiding the creation of shrinkage cracks.

These and further objects of my invention will be set forth in the following specification, reference being had to the accompanying drawings, and the novel means by which said objects are effectuated will be definitely pointed out in the claims.

In the drawings:

Figure 1 is a side elevation, partly in section of my improved truck bolster, showing in dotted lines the body center plate and the king pin connecting this plate with the truck bolster.

Fig. 2 is a plan view of the bolster as viewed in Fig. 1 and Fig. 3 is also a plan view, partly in section as taken along the line 3-3 in Fig. 1, looking in the direction of the arrows.

Figs. 4 and 5 are transverse sections taken along the lines 4-4 and 5-5 in Fig. 1, respectively, looking in the direction of the arrows.

The numeral 10 designates my improved truck bolster which is of hollow section as defined by an upper web 11, a lower web 12, and connecting side walls 13-13. The webs 11 and 12 are each of uniform thickness transversely of the bolster, but may taper longitudinally from the center plate towards each end in accordance with standard prac-

tice, and the side walls 13—13 are also of uniform thickness across any transverse section from the upper web 11 down to a line generally indicated by the numeral 14 in Fig. 1 which extends lengthwise of the bolster and which is substantially at the elevation of the lower web in the region of the guide lugs 15. Below the line 14, the side walls 13 gradually increase in thickness transversely of the bolster down to their junction with the lower web 12. Disposed in the usual location on the upper web 11 intermediate the ends of the bolster is the customary center plate 16 which receives the body center plate 17 and which includes a centrally disposed hole 18 for the reception of the usual king pin 19, said king pin and body center plate being shown dotted in Fig. 1. Except for the tapering disposition of the metal in the side walls 13, the bolster as above described is substantially identical with the present standard form of truck bolster and, aside from the specific arrangement of said side walls, forms no part of the present invention.

As a means of adequately strengthening the bolster and further distributing the load imposed thereon, the following instrumentalities are provided: A truss structure 20 is arranged within the bolster beneath the center plate 16 and comprises a compression member 21 which is bridged across the lower web 12 of the bolster beneath the center plate 16 in a direction lengthwise of the bolster, a tension member 22 which forms a part of the lower web 12, and side walls 23 which depend from the opposite side edges of the compression member 21 in spaced relation to the side walls 13—13 downwardly for junction with the tension member 22, as shown clearly in Fig. 4, the side walls 23 functioning generally as the posts or struts of the truss. In the interest of facilitating drainage and procuring a better casting, the center portion of the compression member 21 may include a hole 24 extended therethrough and the end portions of said member may be cut away as at 25. Similarly, the center portion of the tension member 22 may include a drainage hole 26.

In order to transmit the load from the center plate 16 to the truss 20 a pair of webs 27 extend downwardly from the underside of the upper web 11 adjacent said center plate for junction at their lower extremities with the compression member 21, said webs being spaced from the side walls 13 of the bolster proper and substantially in alignment with the side walls 23 of the truss 20. At the upper extremities of the webs 27, their junction with the upper web 11 may be strengthened by gusset webs 28 which are disposed externally of the webs 27, as shown clearly in Fig. 4, and between the webs 27 as a means of further strengthening the cen-

ter plate 16, a pair of webs 29 extend downwardly from the underside of said plate in substantial alignment with the gusset webs 28 and advantageously disposed with reference to the application of the load on the upper side of the center plate 16, as indicated generically by the numeral 30 in Fig. 1. Adjacent their lower extremities, the webs 29 are bent toward each other, as shown by the numeral 31, and are shaped into a pocket 32 for the reception of the lower end of the king pin 19, the bottom of said pocket including a hole 33 for drainage purposes.

According to the above internal structure of the bolster, it will be obvious that the load imposed on the center plate will be distributed substantially throughout the length of the bolster and will thus avoid any tendency to establish critical, localized stresses in the bottom web 12. This distribution of the load is facilitated by the depending web 29 which, in addition, functions to strengthen the center plate and also to receive the lower end of the king pin 19. This internal, strengthening structure is susceptible of being easily cast and may be adapted to standard forms of truck bolsters without the necessity of making changes in other portions thereof. The tapering construction of the side walls 13 not only assists in strengthening the bolster as a unit and especially in counteracting the tensile stresses present in the lower web 12, but the thickened region at their junctions with the lower web 12 effectually serve to prevent the creation of shrinkage cracks during the cooling of the casting.

While I have shown one set of elements and combinations thereof for effectuating my improved truck bolster, it will be understood that the same is intended for purpose of illustration only and in nowise to restrict my device to the exact forms and structures shown, for many changes may be made therein without departing from the spirit of my invention.

I claim:

1. A truck bolster of hollow section having an internal truss structure disposed wholly beneath the center plate for receiving and distributing a portion of the load through the length of the bolster, the upper member of said truss being subjected to compressive stresses exclusively and spaced from the upper web of the bolster.

2. A truck bolster of hollow section having an internal truss structure disposed wholly beneath the center plate for receiving and distributing a portion of the load through the length of the bolster, the upper member of said truss being subjected to compressive stresses exclusively, and means interposed between said structure and the center plate for transmitting the load.

3. A truck bolster of hollow section having an internal truss disposed beneath the center

- plate for receiving and distributing a portion of the load imposed on said plate, said truss comprising a compression member spaced from the upper web of the bolster and a tension member forming part of the lower web of the bolster.
4. A truck bolster of hollow section having an internal truss disposed beneath the center plate for receiving and distributing a portion of the load imposed on said plate, said truss comprising a compression member and a tension member forming part of the lower web of the bolster, and means interposed between said truss and the center plate for transmitting the load.
5. A truck bolster of hollow section having an internal truss disposed beneath the center plate for receiving and distributing a portion of the load imposed on said plate, said truss comprising a compression member, a tension member forming part of the lower web of the bolster, and side walls depending from said compression member and joining with said lower web.
6. A truck bolster of hollow section having an internal truss disposed wholly beneath the center plate for receiving and distributing a portion of the load imposed on said plate and extending lengthwise of the bolster, said truss having a length greater than the diameter of the center plate and the upper member of said truss being subjected to compressive stresses exclusively, and spaced from the upper web of the bolster.
7. A truck bolster of hollow section comprising an upper web, a lower web, side walls connecting said webs, a truss formed on said lower web beneath the center plate, the upper member of said truss being subjected to compressive stresses exclusively, and means connecting said truss and upper web.
8. A truck bolster of hollow section having an internal truss structure disposed wholly beneath the center plate for receiving and distributing a portion of the load through the length of the bolster, the upper member of said truss being subjected to compressive stresses exclusively, and webs interposed between said structure and the center plate for transmitting the load.
9. A truck bolster of hollow section having an internal truss disposed beneath the center plate for receiving and distributing a portion of the load imposed on said plate, said truss comprising a compression member and a tension member forming part of the lower web of the bolster, and webs interposed between said compression member and the upper web of the bolster for transmitting a portion of the load imposed on said plate.
10. A truck bolster of hollow section having an internal truss disposed beneath the center plate for receiving and distributing a portion of the load imposed on said plate, said truss comprising a compression mem-
- ber, a tension member forming part of the lower web of the bolster, and side walls depending from said compression member and joining with said lower web, and webs extending upward from said side walls for junction with the upper web of the bolster.
11. A truck bolster of hollow section having an internal truss disposed beneath the center plate comprising a compression member and a tension member forming part of the lower web of the bolster, web portions connecting said compression member and the upper web of the bolster, and a reenforcing means comprising webs depending from the center plate and disposed transversely between and connecting said web portions.
12. A truck bolster of hollow section having an internal truss disposed beneath the center plate comprising a compression member and a tension member forming part of the lower web of the bolster, web portions connecting said compression member and the upper web of the bolster, and a reenforcing means comprising webs depending from the center plate and disposed transversely between and connecting said web portions, said reenforcing means being positioned within the peripheral edge of the center plate.
13. A truck bolster of hollow section having an internal truss disposed beneath the center plate comprising a compression member and a tension member forming part of the lower web of the bolster, web portions connecting said compression member and the upper web of the bolster, and a reenforcing means comprising webs depending from the center plate and disposed transversely between and connecting said web portions, said reenforcing webs at their lower extremities extending toward each other and shaped to provide a pocket for receiving the lower end of the king pin.
14. A truck bolster of hollow section having an internal truss structure disposed wholly beneath the center plate for receiving and distributing a portion of the load through the length of the bolster, webs interposed between said structure and the center plate for transmitting the load therebetween, and gusset webs at the junction of the upper extremities of said first named webs with the center plate.
15. A truck bolster of hollow section having an internal truss disposed beneath the center plate comprising a compression member and a tension member forming part of the lower web of the bolster, web portions connecting said compression member and the upper web of the bolster, gusset webs at the junction of the upper extremities of said web portions with the center plate, and a reenforcing means comprising webs depending from the center plate and disposed

transversely between and connecting said web portions.

16. A truck bolster of hollow section, the upper and lower webs each having a uniform thickness transversely of the bolster and the side walls having a transverse uniform thickness above a line between the upper and lower webs and increasing in thickness downwardly therefrom to the junction points with the lower web.

17. A truck bolster of hollow section having a lower web of uniform thickness transversely of the bolster, and side walls having a transverse uniform thickness above a line between the upper and lower webs and increasing in thickness downwardly therefrom to the junction points with the lower web.

18. A truck bolster of hollow section having a lower web of uniform thickness transversely of the bolster, and side walls of transverse uniform thickness above a horizontal line extending longitudinally of the bolster and having substantially the same elevation as the lower web at the bolster ends and increasing in thickness downwardly therefrom to the junction points with the lower web.

19. A truck bolster of hollow section, the upper and lower webs each having a uniform thickness transversely of the bolster, and the side walls having a transverse uniform thickness above a horizontal line extending longitudinally of the bolster and having substantially the same elevation as the lower web at the bolster ends and increasing in thickness downwardly therefrom to the junction points with the lower web.

20. A truck bolster of hollow section comprising an upper web of transverse uniform thickness, a lower web of transverse uniform thickness, side walls connecting said webs and having a transverse uniform thickness above a line between the upper and lower webs and increasing in thickness downwardly therefrom to the junction points with the lower web, a truss formed on said lower web beneath the center plate, and means connecting said truss and upper web.

21. A truck bolster of hollow section, having an internal truss disposed beneath the center plate comprising a compression member and a tension member forming part of the lower web of the bolster, web portions connecting said compression member and the upper web of the bolster, reenforcing means comprising webs depending from the center plate and disposed transversely between and connecting said web portions, and gusset webs aligned with said reenforcing webs and disposed at the junction of the upper extremities of the latter with the center plate.

22. A truck bolster of hollow section having an internal truss disposed beneath the center plate for receiving and distributing a portion of the load imposed on said plate, said truss comprising a compression member,

a tension member forming part of the lower web of the bolster, side walls depending from said compression member and joining with said lower web, and webs extending upward from and in alignment with said side walls for junction with the upper web of the bolster.

23. A truck bolster of hollow section having an internal truss disposed beneath the center plate for receiving and distributing a portion of the load imposed on said plate, said truss comprising a tension member forming part of the lower web of the bolster and a compression member connected at its ends to said lower web and spaced from the upper web of the bolster.

24. A truck bolster of hollow section comprising a lower web portion depressed intermediate the bolster ends and having an internal truss disposed wholly beneath the center plate, the compression member of said truss being spaced from the upper web of the bolster and bridged across a predetermined length of said depressed web portion and the tension member forming part of said depressed web.

25. A truck bolster of hollow section comprising a lower web portion depressed intermediate the bolster ends and having an internal truss disposed wholly beneath the center plate, the compression member of said truss being bridged across a predetermined length of said depressed web portion and a tension member forming part of said depressed lower web, and means interposed between said truss and the center plate for transmitting the load.

26. A truck bolster of hollow section having an internal truss disposed beneath the center plate for receiving and distributing a portion of the load imposed on said plate, said truss having a compression member spaced from the upper web of the bolster.

27. A truck bolster of hollow section having an internal truss disposed beneath the center plate for receiving and distributing a portion of the load imposed on said plate, said truss having a compression member spaced from the upper web of the bolster, and means interposed between said member and the center plate for transmitting the load.

28. A truck bolster of hollow section having an internal truss disposed beneath the center plate for receiving and distributing a portion of the load imposed on said plate and extending lengthwise of the bolster, said truss having a length greater than the diameter of the center plate, the compression member of said truss being spaced from the upper web of the bolster and the tension member forming part of the bolster lower web.

29. A truck bolster of hollow section having an internal truss disposed beneath the center plate for receiving and distributing a

portion of the load imposed on said plate, the compression member of said truss being spaced from the upper web of the bolster, and webs interposed between said compression member and the upper web of the bolster for transmitting the load.

30. A truck bolster of hollow section comprising an upper web of transverse uniform thickness, a lower web of transverse uniform thickness, side walls connecting said web and having a transverse uniform thickness above a line between the upper and lower webs and increasing in thickness downwardly therefrom to the junction point with the lower web, a truss located within the bolster beneath the center plate, the compression member of said truss being spaced from the upper web of the bolster, and means connecting said compression member and upper web.

20 31. A truck bolster of hollow section comprising a lower web portion depressed intermediate the bolster ends and having an internal truss disposed wholly beneath the center plate, the compression member of said truss being bridged across a predetermined length of said depressed web portion and spaced from the upper web of the bolster.

32. A truck bolster of hollow section comprising a lower web portion depressed intermediate the bolster ends and having an internal truss disposed wholly beneath the center plate, the compression member of said truss being bridged across a predetermined length of said depressed web portion, and means interposed between said member and the center plate for transmitting the load.

In testimony whereof, I have subscribed my name.

MARK H. MARTIN.
